UNITED STATES PATENT OFFICE.

OTTO LEUCHS AND EMIL HÜBERT, OF ELBERFELD, GERMANY, ASSIGNEES TO FARBEN-FABRIKEN VORM. FRIEDR. BAYER AND CO., OF LEVERKUSEN, NEAR COLOGNE-ON-THE-RHINE, GERMANY.

SPINNING OF ARTIFICIAL SILK.

No Drawing.

Application filed May 4, 1925. Serial No. 28,010.

To all whom it may concern:

Be it known that we, OTTO LEUCHS and EMIL HÜBERT, citizens of Germany, residing at Elberfeld, State of Prussia, Germany, have invented new and useful Improvements in the Spinning of Artificial Silk, of which the following is a specification.

This invention concerns the spinning of artificial silk, in which the deleterious effect of air has been obviated.

The air contained in the precipitating liquid easily collects in the form of bubbles on the walls or bottom or other parts of the spinning apparatus. These air bubbles gradually increase and finally rise, when, on reaching the spinning jet they cause breaks of the threads or other disturbances.

The subject of the present invention is to avoid the separation of air on the walls of the spinning apparatus by taking the precaution of carefully cleaning the walls, etc., from all centres or bases which might serve for the collection of fine air-bubbles. This can be effected, for instance, by boiling the spinning apparatus with water until completely freed from air and maintaining the whole arrangement in this condition by keeping under water and the like. The air contained in the precipitating liquid then does not find any centres or starting points on the walls of the apparatus, on which to

settle and collect with the result that the detrimental and troublesome formation of air bubbles on the walls no longer occurs. 35

We claim:—

1. In the process of manufacturing artificial silk, the treatment of the spinning apparatus prior to spinning consisting in freeing the surfaces of such parts of the apparatus, which come into contact with the precipitating liquid from accumulated air. 40

2. In the process of manufacturing artificial silk, the treatment of the spinning apparatus prior to spinning consisting in freeing the surfaces of such parts of the apparatus, which come into contact with the precipitating liquid, from accumulated air, by boiling and subsequent immersion under the water or other liquid which has been 50 used for this purpose.

3. In the process of manufacturing cellulose acetate silk, the treatment of the spinning apparatus prior to spinning, consisting in freeing the surfaces of such parts of the apparatus, which come into contact with the precipitating liquid, from accumulated air, by boiling and subsequent immersion under the water or other liquid which has been 55 used for this purpose. 60

In testimony whereof we have hereunto set our hands.

OTTO LEUCHS.
EMIL HÜBERT.
